UNITED STATES PATENT OFFICE.

ERNST KARL GRUHN, OF DRESDEN, GERMANY, ASSIGNOR TO TELAUTOGRAPH, GESELLSCHAFT MIT BESCHRAENKTER HAFTUNG, OF DRESDEN, GERMANY.

FACSIMILE-TELEGRAPH APPARATUS.

SPECIFICATION forming part of Letters Patent No. 759,701, dated May 10, 1904.

Application filed November 21, 1902. Serial No. 132,298. (No model.)

To all whom it may concern:

Be it known that I, ERNST KARL GRUHN, a subject of the King of Prussia, German Emperor, residing at Dresden, Saxony, Germany, have invented certain new and useful Improvements in or Relating to Facsimile-Telegraph Apparatus, of which the following is a specification.

The known transmitting mechanism for facsimile telegraphic apparatus of which the function is based upon the principle of decomposing the motion of the stylus into orthogonal coördinates by levers connected with the stylus and passing over and in contact with resistances (or by levers or the like connected with the stylus and operating rotary contacts or resistances) do not effect a precise decomposition, but merely an approximately exact decomposition of the motion of the stylus. The inexactness is due to the fact that during the motion of the writing-stylus along one coördination-axis an oscillation of the lever of the other coördination-axis is effected, which oscillation owing to the deviation between the arc and subtense causes a displacement of the lever-fulcrum—*i. e.*, an alteration in the length of the lever or drawing means. Thus while during the motion of the writing-stylus parallel to one axis the resistance in the second lever system should not vary, owing to the motion of the writing-stylus in the direction of the second axis being *nil*, nevertheless a variation of the resistance takes place in the letter system, whereby, of course, the reproduction of the motion of the stylus is also unfavorably influenced in every other direction of motion. The extent of the error increases with the length or extent of movement of the lever or drawing means. If it is, however, attempted to render the amplitude of movement so small as to make the error negligible, inconvenient measurements would be obtained.

It is the object of the present invention to dispense with the erroneous variations of the resistance, and this is effected by the arrangement of a curved contact-piece bearing and

gliding upon a resistance arranged along the path of motion of the fulcrum-lever, which contact-piece is connected with the lever and has such a curvature that the consequent displacement of the contact-piece during the oscillation of the lever does not cause a displacement of the contact-point upon the resistance. The shape of the contact-piece is such that the contact-point by the peculiar curvature of the contact-piece is displaced through the simultaneous oscillation by so much as it would advance by the displacement of the lever upon the contact, so that in reality it does not move from its position. From this suppression of the error it results that the contact-point in each of the systems undergoes only the precise displacement upon the resistance which it should undergo owing to the corresponding motion of the coördinates.

The invention is represented in two forms of construction in the accompanying drawings, in which—

Figure 1 shows a top plan view of the apparatus diagrammatically, the straight guide of the lever being omitted for the sake of clearness. Fig. 3 is a lateral view showing only one system, and Fig. 2 is a partial top plan view of the second construction.

1 is the stylus, with which are connected two levers 2 and 2^a, with pivots 3 and 3^a movable in straight guides 4 and 4^a, placed at right angles to one another and carrying the contact-arcs 5 and 5^a. As can be seen from a comparison of Figs. 1 and 2, the contact-arc is situated in the first construction between pivot 3 (or 3^a) and the stylus, while it is on the other side of the pivot in the other construction. The contact-arcs glide upon the resistances 6 and 6^a, arranged beneath the straight pivot-guide. The arrangement is the usual one for facsimile-telegraphs of this type, whereby by varying the resistances 6 and 6^a the electric phenomena in the long-distance branch conductors leading to the receiver are varied accordingly. In the following description the shape given to the contact-pieces will be more

clearly defined. According to the above statements it is necessary to render the extent of displacement of the point of contact between the contact-arc and the resistance precisely 5 equal to the motion performed by the point of the stylus in the direction of the motion of the corresponding component. Thus if the stylus describes, as shown in Fig. 1, an irregular curve $p\ q$ the point of contact v should 10 travel a distance $b\ r\ q$. If the stylus moves from p toward the center of the writing plane, the point of contact should remain stationary. This case will first of all be analytically investigated. Assuming the writing-stylus 15 moves straight from p to m , the fulcrum 3 of the lever will be moved back to the point t through the distance y . The vertex of the contact-arc will then be situated at the point v . The contact-arc therefore must have a determined 20 curvature, so as to prevent the contact-point from being displaced. The curvature will hereinafter be expressed in the form of an equation. The curvature of the arc is a function of the angle α . Suppose the length 25 of the lever-arm is l and the distance $3u=a$. It follows that

$$y=1-(3m); 3m=1 \cos. \alpha.$$

Substituting the equivalent for $(3m)$,

$$y=l(1-\cos. \alpha.)$$

Assuming the distance x is the variable radius of the contact-arc, which varies according to the angle α ,

$$35 \quad \text{Radius } x=a-y=a-l(1-\cos. \alpha.)$$

In order to find the distance through which the point v travels when the stylus passes along the curve $p\ q$, it should be imagined 40 that the stylus moves in a straight line from p to r and then from r to q . During the travel of the stylus from p to r the point v remains stationary according to the above equation. During the motion from r to q the angle α 45 does not vary, and the point v travels through a distance b , which, as can be easily seen, is equal to $r\ q$, as had to be proved. In case the contact-arc is on the opposite side of the

pivot 3, Fig. 2, it has a different curvature, and the following equation prevails:

$$50 \quad x'=a-y=a-l(1-\cos. \alpha.)$$

What I claim as my invention, and desire to secure by Letters Patent, is—

1. In a transmitting device for facsimile 55 telegraphic apparatus wherein the motion of the stylus is decomposed into orthogonal coördinates to effect a variation in the resistance of the line conductors, the combination with a stylus, a lever connected therewith and mounted to have a bodily as well as an oscillatory movement and a fixed resistance body, of a contact moving in unison with the lever and coöperating with the resistance body, said contact having a contact-surface corresponding 60 in shape to a path described on the contact by a fixed point on the resistance body when the stylus is moved transversely in a right line and whereby when so moved the electrical resistance will not be varied; substantially as 65 described.

2. In a transmitting device for facsimile 75 telegraphic apparatus wherein the motion of the stylus is decomposed into orthogonal coördinates to effect a variation in the resistance of the line conductors, the combination with a stylus, two levers connected therewith and mounted on axes having a movement in orthogonal lines with respect to each other and fixed resistance bodies extending in the direction of motion of the lever-axes, of contacts moving in unison with the levers and having contact-surfaces engaging the resistances and corresponding in shape to paths described on the contacts by fixed points on the resistance 80 bodies when the stylus is moved on the orthogonal line of the axis of the opposite lever to that with which the contact is connected; substantially as described.

In testimony whereof I have signed my name 85 to this specification in the presence of two subscribing witnesses.
